[57] CLAIM

[21] Appl. No.: 710,945

The ornamental design for a power drill mounted weeding
tool, as shown and described.

[22] Filed: Jun. 6, 1991

DESCRIPTION

[52] U.S. Cl. D15/139; D8/70

FIG. 1 is a top, front and left side perspective view of a
power drill mounted weeding tool showing my new
design, the broken line depiction of a portion of a power
drill being for illustrative purposes only and forming no
part of the claimed design;

[58] Field of Search 366/343; D8/1, 86, 70;
172/375, 25; 7/114-116; 294/49; D7/688;
175/327, 385; D15/139, 138

FIG. 2 is a right side elevational view thereof;
FIG. 3 is a real elevational view thereof, the opposite
side being the same in appearance;
FIG. 4 is a top plan view thereof; and,
FIG. 5 is a bottom plan view thereof.
